O. MINTON

RADIO RECEIVING APPARATUS

Filed Jan. 19, 1923.

UNITED STATES PATENT OFFICE.

OGDEN MINTON, OF GREENWICH, CONNECTICUT.

RADIO RECEIVING APPARATUS.

Application filed January 19, 1923. Serial No. 613,576.

To all whom it may concern:

Be it known that I, OGDEN MINTON, a citizen of the United States, residing at Greenwich, in the county of Fairfield and State of Connecticut, have invented certain new and useful Improvements in Radio Receiving Apparatus, fully described and represented in the following specification and the accompanying drawing, forming a part of the same.

This invention relates to radio receiving apparatus, and aims to provide a simple and compact apparatus by eliminating the aerial or loop which is customarily a part of such apparatus.

In accordance with the invention the loop or aerial of an ordinary radio receiving apparatus is replaced by a grounded circuit containing a variable inductance, and most desirably also a variable condenser. The inductance may be provided by two inductance coils positioned for mutual inductance and connected in series. The two ends of the coils which are connected together are grounded.

In order that my invention may clearly be understood, I will describe in detail a specific apparatus embodying it. Such an apparatus is illustrated diagrammatically in the drawings, in which:—

Fig. 1 shows the use of a standard amplifying and detecting system as a part of the apparatus; and

Fig. 2 shows a modified form of grounded circuit which may be connected to the amplifying and detecting system shown in Fig. 1.

Apparatus embodying the invention includes a grounded circuit, the nature of which is hereinafter explained, connected across the in-put terminals of a detecting system. The detecting system S which is shown in Fig. 1, for the sake of illustration, is of a standard type heretofore commonly used in loop receiving apparatus. The detecting system illustrated, which may more specifically be termed a vacuum tube amplifying and detecting system, provides for three stages of radio frequency amplification, and two stages of audio frequency amplification. As the nature and connections of such a system are well understood and clearly illustrated in the drawing, they are not herein described in detail,

as they do not in themselves form a part of the invention.

The amplifying and detecting system S is provided with two in-put terminals G and F. The terminal G is connected to the grid element of a three-element vacuum tube V, while the terminal F is connected through the usual A battery with the filament element of this tube.

Across the in-put terminals G, F of the amplifying and detecting system S is connected a circuit 10. The circuit 10 contains two inductance coils 11, 12. One end 13 of the coil 11 is connected by a conductor 14 to the terminal G of the detecting system. One end 14 of the coil 12 is connected by a conductor 15 to the terminal F of the detecting system. The other ends 16, 17 of the coils 11, 12 are connected together by a conductor 18, so that the two coils are connected in series in a circuit connected between the terminals G and F of the detecting system. A conductor 20 extends from any point of the conductor 18 to the ground. A variable condenser 21 is shunted across the coil 11 by conductors 22, 23.

The two inductance coils 11, 12 are positioned for mutual inductance and are mounted for relative movement, so that the inductance linkage between them may be changed.

In the form of the apparatus which I have found most convenient and satisfactory in practice, the two inductance coils 11, 12 are provided by a standard short wave variometer in which the coils are mounted so as to permit a turning of one within the other to vary the inductance linkage between them. In this form of apparatus, the condenser 21 is a standard 43 plate variable condenser.

In using the apparatus which has been described, the grounded circuit is first tuned by varying the relative position of the coils 11, 12 until the signals which are to be received become audible in a telephone connection to the jack J of the amplifying and detecting system S. The apparatus is then tuned more sharply by varying the capacity of the condenser 21, and in this way signals of wave lengths different from that of the desired signals is tuned out.

In the modified grounded circuit illustrated in Fig. 2, the two inductance coils 11', 12' which replace the coils 11, 12 of Fig. 1

are mounted side by side instead of one within the other, and their inductance linkage is varied by swinging one or both of the coils about pivots 24 so as to vary the distance between the coils.

I wish it clearly understood that my invention is by no means limited to the specific arrangement which has been illustrated and described, as I believe my invention provides 10 the first successful receiving apparatus using neither an aerial, nor a loop, and having only one connection to the ground. While I shall not attempt to describe all the changes which may be made in the circuit described 15 without departing from my invention, I wish to note that the apparatus may be made to operate without the use of the condenser 21.

What I claim is:

20 1. Radio receiving apparatus, comprising the combination with a detecting system, of a circuit connecting the in-put terminals of said system and containing two inductance coils connected in series and mounted for 25 relative movement to vary the inductance linkage between them, and a connection from a point of said circuit between said coils to the ground.

2. Radio receiving apparatus, comprising the combination with a detecting system, of 30 a circuit connecting the in-put terminals of said system and containing two inductance coils connected in series and mounted for relative movement to vary the inductance linkage between them, a variable condenser 35 shunted across one of said coils, and a connection from a point of said circuit between the coils to the ground.

3. Radio receiving apparatus, comprising the combination with a detecting system 40 containing a three element vacuum tube and having two in-put terminals which are connected with the grid and filament elements of said tube respectively, of a circuit connecting the in-put terminals of said system 45 and containing two inductance coils connected in series and mounted for relative movement so as to vary the inductance linkage between them, a connection from a point of said circuit between said coils to the 50 ground, and a variable condenser connected between said point of the circuit and the grid terminal of the detecting system.

In testimony whereof I have hereunto set my hand.

OGDEN MINTON.
